UNITED STATES PATENT OFFICE.

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND.

ANCHOR CLAMP.

Application filed April 20, 1927. Serial No. 185,249.

The invention relates to anchor clamps used in connection with the conductors of transmission lines for holding the conductor under strain.

5 The principal object of the invention, generally stated, is to provide an improved clamp so designed that it may be attached to a taut conductor with the insulators attached to it, the arrangement being such that when the 10 load is slackened off from the pulled end of the conductor it is transferred to the insulators without damaging them.

An important object of the invention is 15 to provide a clamp of this character embodying clamping means to which are attached links which in turn are connected to an insulator or string thereof, an arm being furthermore provided on the links for holding the conductor away from the insulators during the slackening off and subsequently to guide 20 the conductor around the insulators.

A still more important object is to provide 25 a clamp of this character in which the connection of the links with the clamping member itself lies along, or substantially along, the longitudinal center line of the conductor so as to obtain a straight line pull, the connection of the links with the clamping means being of a character permitting ready assembly 30 and providing a certain amount of desirable looseness so that the parts may properly accommodate themselves to the line of pull.

Another object is to provide a clamp of 35 this character in which the means for holding and guiding the conductor away from the insulators need not be itself formed as a clamp.

Still another object is to provide a clamp 40 of this character having a bell mouth of considerable length and having a large radius so as to permit the unavoidable vibration of the conductor without the bringing of bending strains at any localized point on the conductor.

45 An additional object is to provide a clamp of this character which is simple and inexpensive to manufacture, easy to assemble and install, positive in action, efficient and durable in service, and a general improvement in the art.

To the attainment of the foregoing and other objects and advantages, the invention preferably consists in the details of construction and the arrangement and combination 50 of parts to be hereinafter more fully described

and claimed, and illustrated in the accompanying drawing in which:

Figure 1 is a plan view of a clamp constructed in accordance with the invention,

Figure 2 is a side elevation thereof, and 60 Figure 3 is a cross section taken on the line 3-3 of Figure 1.

Referring more particularly to the drawing I have shown the clamp as comprising co-acting clamping members 1 and 2 together 65 with suspension means 3 and conductor holding means associated therewith. The member 1 is shown as comprising or formed as an elongated body which may be concavo-convex in cross section as illustrated or which 70 may simply have its upper surface 4 channeled or grooved to receive and support the conductor or cable 5, the member 1 being provided intermediate its ends with any desired number of laterally extending lugs 6 75 apertured for the passage of the arms 7 of U-bolts 8 which straddle the member 2 and which carry nuts 9. At one end the member 1 is formed with a downwardly curved portion or extension 10 for a purpose to be described.

The member 2 is elongated in shape and may likewise be concavo-convex in cross section or simply provided with a channel or groove 11 in its undersurface for substantially conforming engagement with the cable or conductor 5. At points intermediate its ends this member 2 is provided with spaced ribs 12 or is otherwise formed to provide curved seats 13 for the bight portions of the 90 U-bolts 8. When the nuts 9 are applied and screwed down tightly the bolts 8 will act to force the members 1 and 2 into clamping relation to the conductor 5 so that any slippage 95 thereof with respect to the clamp will be prevented.

At its end adjacent the extension 10 the member 2 is provided or formed with a widened head 14 cut back from its end as shown to provide an opening 15 and ears 16 at opposite sides thereof, these ears straddling the member 1 near the extension 10. The ears are formed or otherwise provided with laterally extending trunnions 17 having heads 18 which may be oval or elliptical in shape or otherwise formed to project beyond 100 the trunnions in a direction toward the opposite end of the clamp. The purpose of these trunnions will be hereinafter explained.

The other ends of the members 1 and 2, that is, the ends most remote from the extension 110

10 and trunnions 17, are outwardly flared as clearly indicated at 19 to provide what may be called a bell mouth which has, preferably, a long radius in order to permit lateral movement of the cable or conductor with respect to the clamp, such as must occur during ordinary vibration resulting from wind, etc., without causing the conductor to bend sharply. This is an important feature as it is highly necessary to prevent any bending of the material of the conductor with sufficient abruptness to cause weakening, chafing or breaking as might otherwise occur.

The suspension means for the clamp is here represented as including a pair of links 20 spaced apart and having secured between them a rigid curved or angular arm 21 formed with a diagonal groove 22 with an overhanging flange 23 beneath which the conductor 5 may be engaged for guiding it around a string of insulators, not shown. At one end, the links 20 may be provided with holes 24 for their attachment to whatever is desired, and their other ends are preferably diverged or offset outwardly to straddle the head 14, these second mentioned ends being formed with openings 25 corresponding substantially to the shape of the heads 18 so as to permit engagement upon the trunnions 17. After such engagement is effected it is apparent that upon relative movement of the clamp and links the heads 18 will overlap the links at one side of the openings 25 therein and prevent separation. The curved extension 10 above referred to acts as a guide so that the conductor 5 will be led naturally to the diagonal groove 22 provided for its reception, any kinking or abrupt bending being avoided.

The device is used in substantially the same manner as other anchor clamps, the conductor 5 being engaged between and clamped by the members 1 and 2, the securing action being effected by means of the U-bolts and nuts in an obvious manner. However, it will be observed that the trunnions 17 are located substantially in line with the longitudinal axis of the conductor so that a straight pull will be exerted, any canting or angling being consequently avoided. The cutting back of the material or equivalent structure to define the opening 15 provides the necessary clearance with respect to the cable at this point and gives greater freedom. It will be observed that the clamp is so designed that it may be attached to a taut conductor with the insulators attached to it. When the load is slacked off from the pulled end of the conductor it is transferred to the insulators without damaging them. The rigid arm 21 will act to hold the conductor or cable away from the insulators during the above mentioned slackening off process and will subsequently guide the conductor in its direction around the insulators. By providing the diagonal slot or groove 22 it is apparent that it will be unnecessary to

provide a clamp for this portion of the conductor though it is conceivable that one might be used if found necessary, it being old to do so.

From the foregoing description and a study of the drawing it will be apparent that I have thus provided a comparatively simple and inexpensive clamp which embodies only a few parts, which is provided with adequate means for clamping and suspension, and which is in every way well capable of performing all the functions for which it is intended. It is believed that the construction, operation and advantages will be readily apparent to one skilled in the art without further explanation.

While I have shown and described the preferred embodiment of the invention and certain specific details of construction, it should be understood that the disclosure is merely an exemplification of the general features involved and that the right is reserved to make all such changes as will not depart from the spirit of the invention or the scope of the claims hereunto appended.

Having thus described the invention, I claim:

1. In a clamp of the character described, the combination of coacting clamping members adapted to be clampingly engaged upon and with a conductor, and suspension means connected therewith substantially in line with the longitudinal axis of the conductor, and an arm carried by the suspension means at the intermediate portion thereof and engageable with the conductor at a point spaced from the clamping members.

2. In a clamp of the character described, the combination of a pair of members adapted to receive a conductor between them, means for holding said members in clamping engagement with respect to the conductor, outwardly extending trunnions formed integrally on one of the members, and links pivotally engaged with said trunnions.

3. In a clamp of the character described, the combination of a pair of members adapted to receive a conductor between them, means for holding said members in clamping engagement with respect to the conductor, outwardly extending trunnions formed integrally on one of the members and links pivotally engaged with said trunnions, said trunnions being located substantially in line with the longitudinal axis of the conductor.

4. In a clamp of the character described, the combination of a pair of members adapted to receive a conductor between them, means for holding said members in clamping engagement with respect to the conductor, outwardly extending trunnions on one of the members, and links pivotally engaged with said trunnions, said trunnions being located substantially in line with the longitudinal axis of the conductor and having heads pro-

jecting beyond one side thereof, said links having openings to receive said heads and to be overlapped thereby upon relative longitudinal movement of the assembled clamping members with respect to the links.

5. In a clamp of the character described, a pair of members having their confronting faces grooved for substantially conforming reception of a conductor, means securing said members in clamping relation to the conductor, one of said members having a downwardly curved extension at one end and the other having its corresponding end arranged in straddling relation to the first named member adjacent the extension, said end of the second named member being formed with laterally extending trunnions, and links pivotally engaged upon said trunnions.

6. In a clamp of the character described, a pair of members having their confronting faces grooved for substantially conforming reception of a conductor, means securing said members in clamping relation to the conductor, one of said members having a downwardly curved extension at one end and the other having its corresponding end arranged in straddling relation to the first named member adjacent the extension, said end of the second named member being formed with laterally extending trunnions, and links pivotally engaged upon said trunnions, said trunnions having means for preventing disconnection from the links.

7. In a clamp of the character described, a pair of members having their confronting faces curved in cross section, said members being adapted to receive a conductor between them, one member having laterally extending lugs, U-bolts straddling both members and passing through said lugs, nuts on said bolts for clamping the members upon the conductor, trunnions projecting laterally in opposite directions from one end of one of said members, and links having openings therein engaged upon said trunnions.

8. A clamp of the character described comprising a pair of clamping members adapted for engagement upon a conductor, bolt means for securing said members in clamping relation to the conductor, one of said members having a downwardly curved extension at one end, the other member having its corresponding end enlarged to define a head formed with an opening and ears at opposite sides of the opening, said ears being arranged in straddling relation to the first named member near the curved extension thereon, trunnions projecting laterally from the ears, and links straddling the ears and pivotally engaged upon the trunnions.

9. A clamp of the character described com-

prising a pair of clamping members adapted for engagement upon a conductor, bolt means for securing said members in clamping relation to the conductor, one of said members having a downwardly curved extension at one end, the other member having its corresponding end enlarged to define a head formed with an opening and ears at opposite sides of the opening, said ears being arranged in straddling relation to the first named member near the curved extension thereon, trunnions projecting laterally from the ears, and links straddling the ears and pivotally engaged upon the trunnions, the trunnions having elongated heads and the links having correspondingly elongated openings.

10. In a clamp of the character described, a pair of members engageable upon a conductor, means for clamping said members together, integral trunnions at one end of one of the members, links engaged upon the trunnions for anchoring the assembled members, the other ends of said members being flared into bell mouth form.

11. In a clamp of the character described, a pair of members engageable upon a conductor, means for securing the members together in clamping relation to the conductor, trunnions projecting laterally from one member at one end thereof, a pair of links pivotally engaged upon said trunnions, and a rigid arm depending from the links and having a diagonal undercut groove therein for the reception of the conductor.

12. In a clamp of the character described, a pair of members engageable upon a conductor, means for securing the members together in clamping relation to the conductor, trunnions projecting laterally from one member at one end thereof, a pair of links pivotally engaged upon said trunnions, and a rigid arm depending from the links and having a diagonal undercut groove therein for the reception of the conductor, the other of said members having a downwardly curved extension thereon beneath the trunnions for leading the conductor to said groove.

13. In a clamp of the character described, a clamping part, hinged links attached thereto, a rigid arm carried by the links, and a means for engaging and guiding the conductor at the end of the rigid arm.

14. In a conductor clamp of the character described, a clamping part, hinged links attached thereto, and a rigid arm carried by the links, the arm having a diagonal undercut groove therein for the reception of the conductor held by the clamping part.

In testimony whereof I affix my signature.

KENT A. HAWLEY.
